CLAIM

The ornamental design for a mobile PDA terminal, as shown and described.

DESCRIPTION

FIG. 1.1 is a front view of a mobile PDA terminal, showing our new design;

FIG. 1.2 is a back view thereof;

FIG. 1.3 is a left view thereof;

FIG. 1.4 is a right view thereof;

FIG. 1.5 is a top view thereof;

FIG. 1.6 is a bottom view thereof;

FIG. 1.7 is a front perspective views thereof; and

FIG. 1.8 is a back perspective views thereof.

(Continued)

The broken lines in FIGS. 1.6 and 1.8 depict a portion of the mobile PDA terminal that forms no part of the claimed design.

1 Claim, 6 Drawing Sheets
